Gro-ables by Miracle-Gro dated Apr. 14, 2013, found online [Apr. 5, 2014] http://www.amazon.com/Miracle-Gro-Gro-ables-Vegetable-Herb-Garden/dp/B00C88DV6M/ref=cm_cr_pr_pb_t.*Primary Examiner — Robert M Spear*Assistant Examiner* — Marissa Cash(74) *Attorney, Agent, or Firm* — Hunton & Williams LLP(57) **CLAIM**

We claim the ornamental design for a planting container, as shown and described.

DESCRIPTION

FIG. 1 depicts a perspective view of an outer shell of a planting container.

FIG. 2 is a front elevational view thereof.

FIG. 3 is a rear elevational view thereof.

FIG. 4 is a side elevational view thereof.

FIG. 5 is an opposite side elevational view thereof.

FIG. 6 is a top plan view thereof; and,

FIG. 7 is a bottom plan view thereof.

The broken lines in the drawings illustrate environmental structure on the article and form no part of the claimed design.
